UNITED STATES PATENT OFFICE

WALTER E. CARR, OF SPOKANE, WASHINGTON

DRILLING MACHINE

Application filed March 8, 1930. Serial No. 434,274.

My present invention relates to improvements in drilling machines of the pneumatically operated, reciprocating type usually employed in mining work and tunnel operations, and the invention relates particularly to the feed and control mechanism for automatically advancing the drill and machine or motor to its work. As is well known to those familiar with the operation of such machines, a stationary frame is supported, as by a swivel joint, upon a fixed column, and the operating part of the drilling machine is supported in this frame and advanced relatively to the frame as the drilling progresses. In a well known type of machine, the operator usually grasps the air throttle lever in his left hand and thereby controls the pneumatically operated, reciprocable motor and its drill. The right hand of the operator is usually employed to turn a crank, thereby rotating a feed screw bar (which bar is stationary) for advancing the drilling machine. Due to the air pulsations in the pneumatically operated reciprocating motor, the drill is reciprocated, and because of the these vibrations, known as the "kick" of the drilling machine, the latter is bodily reciprocated, but slightly, with relation to its supporting frame. In carrying out my invention I utilize the power in the "kick" for automatically advancing or feeding the drilling machine with relation to its supporting frame and thereby dispense with the usual manually operated feed for the drilling machine. The continuous vibrations or "kick" of the usual, standard, manually-fed drilling machine, passing through both hands and arms of the operator, subjects him to an undesirable nervous strain, which strain is materially reduced by the use of my invention, and the automatic feed of the drilling machine in lieu of the manual feed releases one hand of the operator for other uses. The invention consists in certain novel combinations and arrangements of parts whereby the above indicated results are attained. In the accompanying drawings I have shown a well known type of drilling machine equipped with the automatic feed of

my invention, and the parts are combined and arranged therein in accord with one mode that I have so far devised for the practical application of the principles of my invention.

Figure 1 is a view in side elevation showing a drilling machine and its stationary frame, part of the latter being omitted for convenience of illustration.

Figure 2 is an enlarged detail exterior view, as seen from the rear of Figure 1, showing part of the stationary feed, rack-bar with the operating pawl in reverse position from that of Figure 1, and showing also a brake device for the drill machine.

Figure 3 is a sectional detail view at line 3-3 of Figure 2.

Figure 4 is a longitudinal sectional view at line 4-4 of Figure 3 with the operating pawl in position of Figure 2 for feeding or advancing the drilling machine.

Figure 5 is a detail sectional view at line 5-5 of Figure 2 showing particularly the brake device for the drilling machine.

In order that the general arrangement and relation of parts may readily be understood I have shown in Figure 1 a standard type of drilling machine for use in mines and in tunnel work, and employing the usual reciprocating drill 1. The drilling machine includes the cylinder 2 with the front head 3 and rear head 4, and the hose for compressed air or other motive fluid is introduced to the cylinder at the port 5. By dotted lines a reciprocating valve 6 is illustrated for controlling the admission of air to the piston 7 that reciprocates in usual manner with the drill or bit 1.

The throttle lever 8 is usually grasped in the left hand of the operator for controlling admission of the compressed air or other motive fluid to the interior of the cylinder. The parts thus described I shall hereinafter refer to as the drill with its bit 1, and it will be understood that the bit is reciprocated for delivering hammer blows as it is turned for drilling the hole.

Under the air pulsations for reciprocating the bit, the drill as a whole is also longitudinally reciprocated with relation to the supporting frame or tubular housing 9 that is

known as the feed shell. This shell is stationary, and it is provided with a boss 10 that is properly coupled or connected with a swivel joint, not shown, and the joint and shell are supported upon an upright column, not 5 shown.

I utilize the longitudinal vibration or reciprocation of the drill, (known as a "kick") with relation to the shell 9 for feeding or advancing the drill with relation to the shell, 10 and the latter forms the guiding support for the drill.

Within the feed shell is located a stationary rack bar 11 secured at the front end of the machine by nut 12, and clamped at the 15 rear end of the machine in a sleeve 13 forming an extension of the shell. A lock nut 14 and collars 15 are used to fasten the rack bar at the rear end of the machine, and it will be understood that the rack bar and the feed 20 shell which encloses it are fixed or stationary with relation to the drill.

At the rear end of the drill is mounted a hollow feed block 16 which is fashioned with diverging, perforated lugs 17, and a pair of 25 tie bolts 18 connect these lugs with a cylinder bushing 19 that has perforated ears 20 for the bolts. Nuts 21 at the ends of the bolts are used to secure the tie bolts, and in this manner the feed block is rigidly mounted on and at 30 the rear of the drill.

The hollow block has a bushing 22 through which the rack bar passes, and in Figure 1 a sleeve 23, forming part of the cylinder, surrounds the bushing, and the parts are locked 35 together with a lock, nut 24 threaded on the end of the bushing 22.

The lower end of the block, the bushing, sleeve and nut are designed to travel forward in the shell 9 as the drill is fed or advanced to 40 its work.

For co-action with the stationary rack bar I mount an operating pawl in the hollow block, and this pawl is reversible to permit forward or rearward travel of the drill with 45 relation to the shell. The reversible pawl has two arms 25 and 26 and a head 27 and it is enclosed within a recess 28 of the hollow block. The head is mounted upon and fixed by a clutch 30' to a rack pin 29 that may oscillate or rather be oscillated on the bearing or journal 30 of the pin, a nut 31 being used to hold the pin in its bearings. A replaceable sleeve 41 may be used to support the pin 29 at its end adjacent the nut 31.

The pawl is manually controlled and in connection with it I use a snap spring 33 that holds one or the other of the pawl-arms 25, 26 in contact with the rack bar. The lever 60 arm 32 rigid with the pin 29 is used to swing or rock the pawl, and the spring is coiled about a pin 34 that is secured in a lug 35 of the lever arm. The spring pin has a bearing head 36 in a socket in the feed block, 65 which as seen in Figure 4 is out of line with

the axial centers of the bearing for pin 29 and of the lug 35, but the bearing point 36 is located at a point between the extreme opposite positions of the lever arm 32. Thus, in Figure 4 the pawl is turned so that the arm or detent 25 engages the teeth of the rack bar, and the spring holds the pawl for this engagement. By swinging the lever to the right in Figure 4 to the position of Figure 1, the detent 25 is disengaged and the 70 detent or arm 26 engages the rack bar, thus permitting the spring to hold the pawl in released position. In Figure 4, as the drill operates under pulsations of air, the drill is longitudinally reciprocated, or "jumps" 75 thus providing the usual "kick." A rearward movement, under the kick is prevented by the co-action of the detent 25 and the rack bar, but upon the forward jump, following the kick-back, the drill advances the distance 80 of a tooth of the rack bar and the detent therefore engages the next forward tooth of the rack bar. The continuous operation of the drill for reciprocating the bit ultimately 85 and automatically feeds the drill to the limit 90 of its forward position, after which the pawl is reversed and the drill is retracted in usual manner for another advance movement or feed.

It will be understood that the drill may 95 be used in horizontal position, or disposed at an angle to the horizontal, and in the latter instance it is desirable to control, as by a brake, the relative movement or sliding of the drill with relation to the frame or 100 housing or feed shell 9, which shell is of course also disposed at an angle and parallel with the drill.

For this purpose I employ a friction brake device between the drill and its feed bar, or rack bar, the brake being located in the hollow feed block and co-acting therewith. The brake includes a split, expanding shoe or nut 37 located in a recess 38 in the feed block at one side of the rack bar or feed bar 11 and adapted to contact with the rack bar and with the wall of the recess in the block. An expanding, tapered screw 39 is threaded at a suitable angle in the expanding block or nut, and the screw is turned by use of the handle or head 40. The screw may be turned as desired to increase or diminish the friction between the brake shoe and the adjoining friction faces, thus retarding the movement of the drill, or freeing the drill, but of course the friction is not sufficient to stop the bodily reciprocating movement of the drill under the air pulsations or impulses in the pneumatic motor of the drill.

Having thus fully described my invention, what I claim as new and desire to secure by Letters Patent is:—

1. In a drilling machine as described, the combination with a feed shell and its stationary rack bar, of a relatively movable drill, a feed block mounted on the drill and

enclosing part of the bar, a two-armed pawl pivoted in the block for co-action with the bar, means for shifting the pawl, means for releasing the pawl from the bar, an expandible brake shoe between the feed block and the rack bar, and means for expanding the shoe.

2. In a drilling machine as described, the combination with a feed shell and its stationary rack bar, of a relatively movable drill, a hollow feed block mounted on the drill, a reversible pawl pivoted in the block for co-action with the rack bar, a snap spring for retaining the pawl in shifted position, an expanding brake shoe in the block for friction engagement with the rack bar, and means for expanding the shoe for the purpose described.

3. In a motive fluid operated reciprocating drill receiving impulses under pressure, the combination with a stationary guide for the drill and a feed block on the drill, of co-acting means on the feed block and guide actuated under the "kick" of the drill for feeding the drill, an expandible friction member between the guide and the feed block for retarding the movement of the "kick", and means for expanding said member.

In testimony whereof I affix my signature.
